(57) **CLAIM**

The ornamental design for a wind turbine, as shown and described.

DESCRIPTION

1. Wind turbine
- 1.1 : Front perspective
- 1.2 : Rear perspective
- 1.3 : Front
- 1.4 : Back
- 1.5 : Left
- 1.6 : Right

Throughout the reproductions, the wind turbine is shown with a symbolic break in its length. The appearance of any portion of the article beyond the break line forms no part of the claimed design. In the reproductions, the broken lines are for the purpose of illustrating environment only and form no part of the claimed design.
